UNITED STATES PATENT OFFICE.

LOUIS L. KROUPA, OF BERWYN, ILLINOIS.

ELECTRIC-CIRCUIT TESTER.

1,370,751.

Specification of Letters Patent.

Patented Mar. 8, 1921.

Application filed September 4, 1917. Serial No. 189,605.

To all whom it may concern:

Be it known that I, LOUIS L. KROUPA, a citizen of the United States, and a resident of the city of Berwyn, county of Cook, and 5 State of Illinois, have invented certain new and useful Improvements in Electric-Circuit Testers, of which the following is a specification.

My invention relates to improvements in 10 electric circuit testers, and has for its object the production of a device of this character, through the medium of which a plurality of circuits may be separately and expeditiously tested for the detection of breaks 15 or poor connections interfering with the proper flow of current through the conductors.

Other objects will appear hereinafter.

The invention consists in the combinations 20 and arrangements of parts hereinafter described and claimed.

The invention will be best understood by reference to the accompanying drawings forming a part of this specification, and in 25 which,

Figure 1 is a partially diagrammatic plan view of a circuit box, in connection with the circuit wires of which is shown a tester embodying the invention,

30 Fig. 2, a central section through the tester, and

Fig. 3, a fragmental side elevation of the tester.

The preferred form of construction as 35 illustrated in the drawings is shown in connection with conventional circuit box 4, the pairs of branch circuit terminals being illustrated at 5 and 5'. The conductor wires co-operating with said terminals 5 and 5' are 40 illustrated at 6 and 6', respectively.

In the connection of the tester forming the subject matter of this application with the conductor wires 6 and 6', each pair of conductor wires 6 and 6' has bridge wires 45 7 extended therefrom, the wires 7 cooperating with each pair of circuit wires 6 and 6' being connected with spaced contacts 8 and 8', mounted in the body or supporting element 9 of the tester. The latter is adapted to be secured to any suitable support, such as a wall or the like, in the vicinity of the circuit box or other instrument in connection with which the same is employed. The contacts 8 and 8' are spaced apart and 50 insulated from each other so that each bridging circuit will be broken at the terminals

or contacts 8 and 8' therein. The body 9 of the tester is hollow, the same being provided with pipes or nipples 10 for the passage of the wires 7 as seen in the several 60 views.

Mounted upon the front side of the tester body 9 is an electric lamp 11, the terminals of which are connected by conductor wires 12 with brushes 13 and 13' carried at the 65 free end of an arm 14, mounted for pivotal or rotary movement about an axis 15 provided centrally at the front side of said body 9. Upon the arm 14 is provided a suitable handle 16 to facilitate manual 70 rotary adjustment of the same. The pairs of contacts 8 and 8' are arranged in circular formation about the axis 15 and are so spaced, that in the rotary adjustment of arm 14, the brushes 13 and 13' will successively 75 engage with said pairs of contacts. The arrangement is such, as will be seen, that when said brushes 13 and 13' are brought into engagement with any pair of contacts 8 and 8', an electrical connection will be established 80 between said contacts through the lamp 11. Thus it will be seen that any pair of the circuit wires 6 and 6' may be bridged through the lamp 11 by simply adjusting the arm 14 into engagement with the corresponding 85 contacts 8 and 8'. All of said circuit wires being connected with contacts provided upon the tester body, it will be seen that said circuits may be readily and expeditiously tested through simply adjusting the arm 14 into 90 successive registration with the pairs of contacts. In case of a break in any of said circuits the lamp will not light, or in case of a bad connection in any of said circuits, the lamp will glow very dimly or flicker. Thus 95 it will be seen that each circuit may be tested to detect any trouble.

While I have illustrated and described the preferred form of construction for carrying my invention into effect, this is capable of 100 variation and modification without departing from the spirit of the invention. I, therefore do not wish to be limited to the precise details of construction set forth, but desire to avail myself of such variations and 105 modifications as come within the scope of the appended claims.

Having described my invention what I claim as new and desire to secure by Letters Patent is:

A testing device for external circuits comprising an electric switch consisting of a

support, an arm rotatably mounted on said support, a pair of spaced contacts on said arm, a plurality of contacts on said support, said contacts being arranged in pairs, the 5 pairs of contacts being arranged in circular formation in the path of the contacts on the arm, and those of each pair in radial relation, a signal on said support, conductors extending from the contacts on said arm to 10 adjacent the support of the arm, and flexi-

ble conductors extending therefrom to said signal, substantially as described.

In testimony whereof I have signed my name to this specification in the presence of two subscribing witnesses.

LOUIS L. KROUPA.
